United States Patent Office

Des. 229,632

Patented Dec. 18, 1973

229,632

TRASH AND WASTE COMPACTOR

Ira J. Jackson, Overland Park, Kans., and Leroy D. Williams, Kansas City, Mo., assignors to Trans-World Compactors, Inc., Overland Park, Kans.

Filed Feb. 25, 1972, Ser. No. 229,618

Term of patent 14 years

Int. Cl. D15—99

U.S. Cl. D55—1 B

FIG. 1 is a front perspective view of the trash and waste compactor showing our new design;

FIG. 2 is a front perspective view with the access means in the open position;

FIG. 3 is a rear elevational view; and

FIG. 4 is a left side elevational view of the closed compactor.

We claim:

The ornamental design for a trash and waste compactor, as shown and described.
